UNITED STATES PATENT OFFICE.

MAX BAUMGÄRTEL, OF RODEWISCH, GERMANY.

MEANS FOR CONVEYING AWAY EXHAUST GASES FROM MOTOR CARS IN GARAGES.

Application filed November 2, 1926, Serial No. 145,838, and in Germany August 31, 1926.

In garages it is not advisable to let the engines run for a long time as the poisonous carbon dioxides of the exhaust gases are liable to cause poisoning.

5 This invention relates to the ventilation of garages for one or more motor cars, whereby the exhaust gases are led off from the exhaust pipe of the motor car and conducted directly into the atmosphere, troublesome 10 noises being deadened at the same time. If one ventilating arrangement is designed for several motor cars shutting off devices are provided which are of such construction that if only one of the connections is used, the 15 exhaust gases are always conducted into the atmosphere. Flexible metal tubes are used as connections for the motor cars so that free movability of the motor cars is not impeded and when a motor car is started the exhaust 20 pipe is automatically disconnected from the ventilating device.

A ventilating device according to the invention is shown, by way of example, in the accompanying drawing in which:—

25 Fig. 1 shows in side elevation a device for a single car.

Fig. 2 shows in plan view a device for several cars.

30 Fig. 3 shows in horizontal section and in vertical section the ventilation pipe with shutting off valve in the shutting off posi-

tion. Fig. 4 shows similar views the shutting off flap being in the open position.

In the garage *a* a ventilation means, *e*, *f* to the outer side is arranged to which by flexible metal tubes *d* the exhaust *c* of the motor car is connected. The exhaust gases of the engine are thus conducted directly into the atmosphere. The silencers *f* might be arranged as absorbers to avoid troublesome 40 noises. In order that to one ventilation device several motor cars may be connected shutting off elements *h* are inserted into the ventilation tube *g* so that, if only one car is connected to the device, the exhaust gases 45 can not flow back into the garage by the metal tubes *d* which are not connected with a car.

I claim:—

A ventilation means for garages, comprising in combination a ventilation pipe, silencers, one for each car, mounted on said ventilation pipe and projecting to the outer side of the garage, flexible metal tubes branching from said ventilation pipe and designed to 55 be connected to the exhaust pipes of the motor cars and shutting off valves in said ventilation pipe for preventing the back flow of the exhaust gases into the garage.

In testimony whereof I affix my signature.

MAX BAUMGÄRTEL.
